United States Patent Office

Des. 229,457
Patented Dec. 4, 1973

229,457

CHILD'S DRESSING TABLE OR SIMILAR ARTICLE

Nathanael W. Mathieson, Meadow Lark Road,
Vernon, Conn. 06086

Filed Dec. 17, 1970, Ser. No. 26,544

Term of patent 14 years

Int. Cl. D6—01

U.S. Cl. D6—14

FIG. 1

FIG. 2

FIG. 3

FIG. 4

FIG. 5

FIG. 6

FIG. 7

FIG. 1 is a front, top and right end perspective view of a child's dressing table or similar article, showing my new design;

FIG. 2 is a left end elevational view;

FIG. 3 is a right end elevational view;

FIG. 4 is a rear elevational view;

FIG. 5 is a front elevational view;

FIG. 6 is a top plan view; and

FIG. 7 is a bottom plan view thereof.

I claim:

The ornamental design for a child's dressing table or similar article, as shown.
